UNITED STATES PATENT OFFICE.

EZECHIEL WEINTRAUB, OF SCHENECTADY, NEW YORK, ASSIGNOR TO GENERAL ELECTRIC COMPANY, A CORPORATION OF NEW YORK.

PRODUCING LIGHT BY ELECTRICITY.

1,086,104.

Specification of Letters Patent.

Patented Feb. 3, 1914.

Application filed February 26, 1902. Serial No. 95,664.

To all whom it may concern:

Be it known that I, EZECHIEL WEINTRAUB, a subject of the Czar of Russia, residing at Schenectady, county of Schenectady, State of New York, have invented 5 certain new and useful Improvements in Producing Light by Electricity, of which the following is a specification.

The invention which I have hereinafter 10 described relates to certain improvements in vapor electric apparatus of that type in which electrical energy is converted into light through the medium of vaporous or gaseous matter maintained in a luminescent 15 condition by the electric current. In an application filed concurrently herewith, I have described and have claimed broadly certain features of invention whereby a lamp of this character may be started into operation, together with other correlated features 20 unnecessary here to mention. In the present application I propose to disclose certain modified means for operating the lamp, the novel features of which will be pointed out 25 in the appended claims and described in detail in the following specification, in which—

Figure 1 represents one embodiment of my invention, and Fig. 2 a different form 30 of the invention.

I will premise my description of these detailed arrangements by stating that in lamps of the general character mentioned, various difficulties and disadvantages have 35 heretofore been attendant upon the means employed for starting purposes. The usual method of starting the arc, of which of course there are various modifications, is to impress upon the terminals of the lamp, for 40 a certain period or periods, a high electro-motive force, many times greater in value than the normal electro-motive force at which the lamp is intended to operate. This starting electro-motive force operates or at 45 least appears to operate to break down the high initial resistance between the terminals of the lamp, whereupon the lamp starts.

My present invention, among other valuable features, provides means operating 50 automatically or otherwise whereby a lamp of the type mentioned will start into operation by the utilization of electro-motive force no greater than that impressed upon the lamp circuit by the supply mains. The 55 starting is performed by producing locally

within the lamp ionized vapor which, due to the migration of its ions as I at present believe, permits the lamp to be started into operation by the application of the normal voltage to its terminals. After the lamp has been started, the supplemental or auxiliary source of ionized vapor may if desired be cut out of circuit, and to perform this function as well as to initiate the production of ionized vapor, I may make use of the arrangements shown in the drawings above referred to.

Referring to Fig. 1, the lamp will be seen to consist of a main tube 1 of indefinite length as indicated by the dotted lines 2. 69 This tube may be exhausted through a suitable channel as for example the tubular projection sealed off as shown. At either end of the lamp are electrodes, the lower electrode consisting of a body of vaporizable material preferably of mercury filling a narrow downward extension 4 of the lamp and also a small portion of the main body of the tube as indicated. The downward extension 4 is provided with a platinum or 70 other leading-in wire or terminal 5 sealed into the tube. The upper end of the tube is provided with an electrode 6 which cooperates with the main electrode at the lower end of the lamp. This upper electrode may 75 be formed of various materials such for example as a mixture of graphite and clay which possesses the valuable advantage that it does not readily occlude gases, or, if it does do so, it exercises no tenacious hold 80 upon the gases during the exhaustion and initial heating of the lamp. This electrode may be connected by a suitable sealed-in wire 7 with a supplemental evacuated chamber 8, the object of which is to relieve the 85 pressure upon the joint between the wire 7 and the surrounding glass, thereby reducing the danger of deterioration of the vacuum of the main tube through the leakage of air about the sealed-in wire 7. This wire 7 is electrically connected to a coiled or 90 other extensible wire 9 having its outer end sealed through the wall of the chamber 8 and forming an external terminal 10 through 95 which the main current is fed to the lamp. 100

In co-operative relation to the body of mercury forming the lower electrode or cathode of the lamp, is mounted an electrode 11 which is arranged to act as a supplemental anode. This electrode, which may be of

a material not readily vaporizable, is supported within the lower portion of the lamp, and, as shown in Fig. 1, is carried by a sort of septum 12 formed in a tubular projection 13. 5 The resulting inclosed chamber 14 is exhausted and through it passes a suitable electrical connection such as a wire 15 sealed through the wall of this chamber and projecting outside to form an external terminal 16.

Connections from mains 17-18 supplying direct current may be made to the lamp as indicated, the negative main being connected through a switch 19 to the terminal 15 5 communicating with the body of mercury which constitutes the cathode of the lamp, the other main 17 being joined by branch conductors with the main terminal 10 and the supplemental terminal 16 respectively. 20 In these branches are inserted resistances which may be adjustable.

To start the lamp, which may be suspended from a ring 20', it may be slightly shaken or moved about its suspension so as 25 to cause the body of mercury to come into contact with the supplemental anode 11. This contact, being of course immediately broken as the mercury recedes, causes an arc or discharge of current to take place, which 30 discharge sets free or produces mercury vapor in an ionized condition. The ions thus freed travel along the static lines of force, or otherwise progress from one main terminal to the other, and under suitable conditions cause an apparently instantaneous 35 starting of the current between the main terminals of the lamp, in the accomplishment of which the lamp is filled with a brilliant whitish light. Of course the physical 40 operation which takes place in starting the lamp may differ from that which I have above mentioned and which at present appears to me to be a reasonable explanation of the phenomena observed, but it is obvious 45 that this as well as various other explanations as to the theory of operation of the lamp may be indulged in without affecting the value of my invention, the mode of practising which may, with the 50 aid of information which I have given herein, be carried out successfully in the absence of any certain knowledge as to the nature of the physical actions which take place.

55 As I have described in an application filed concurrently herewith and referred to above, it appears to be necessary to the proper operation of the starting means for my lamp that the vacuum should be of as 60 high a degree as possible. I have found that a vacuum represented by a column of mercury of a height of about one thousandth of a millimeter gives most excellent results.

65 In Fig. 2 I have shown a lamp similar

in many respects to that shown in Fig. 1 but differing therefrom in that it starts into operation automatically upon turning on of the current. The supplemental anode 20 in this lamp, instead of being mounted out of contact with the mercury cathode 21 of the lamp, is suspended by a spring or other support 22 in a tubular chamber 23 communicating with the interior of the lamp, the suspension being such as to allow 70 the lower portion of the anode to dip into the mercury 21 as indicated. The spring 22, which is of conducting material, is connected electrically through a supplemental exhausted chamber 24, of a character similar to those already described, with the external terminal 25 sealed through the walls of this supplemental chamber. This terminal is connected to one of the direct current mains 17-18 and includes in the 75 connecting circuit a solenoid 26 and two contacts 27 adapted to be connected by a bridging contact 28 controlled magnetically by a solenoid 29 operatively related to a magnetic core 30 carrying the bridging contact. The supplemental anode 20 being formed of magnetic material and the solenoid 26 being mounted about the tubular extension 23 within operative relation to this anode 20 which acts as a core for the 80 solenoid, it will be seen that when the lamp switch 31 is closed current will flow through the solenoid which will immediately draw its core of magnetic material 20, constituting an anode, out of engagement with the 85 body of mercury 21, thereby striking an arc or causing a similar flow of current which, by causing ionized mercury vapor to be set free, initiates the flow of the main current of the lamp throughout the length of the 90 main tube 1 in a manner already briefly referred to. As soon as the main current starts, the solenoid 29 acting upon its core 95 30 immediately withdraws the bridging contact 28 and so cuts out of circuit the starting device already described. If desired, however, this cut-out device may be omitted as in Fig. 1; while in Fig. 1, although I have shown no means either manual or otherwise for cutting out the supplemental circuit, such means may be provided.

Although the automatic cut-out to which I have heretofore referred may be used or not, as desired, to interrupt the supplemental or auxiliary circuit, it need not always, when used in this connection, be arranged to interrupt the circuit but may, under certain conditions, be employed to vary the resistance of this circuit by opening or closing a short circuit about a portion or all of the resistance in this supplemental circuit; and further it may, if desired, be adjusted so as to perform these functions at any selected current value. Thus if it is 100

desired to run current in the main tube at a low value, for example, the cut-out may be arranged so as to short-circuit a portion of the resistance in the supplemental circuit, thereby increasing the current flow therein and so maintaining stable operation of the lamp at the selected low current value. Or it may be adjusted to reduce the supplemental circuit current when the main arc starts, since when the main arc is in operation the supplemental arc will run on lower current.

What I claim as new and desire to secure by Letters Patent of the United States, is,

1. The combination in a vapor electric apparatus, of an exhausted envelop, main electrodes therefor, one of which has a conducting extension perpendicular to a line joining said main electrodes and is of vaporizable material and a non-vaporizable supplemental electrode co-operatively related to the conducting extension of the last mentioned electrode.

2. The combination in a vapor electric apparatus, of main electrodes, one at least of which is of mercury and has an extension on its edge, and a supplemental electrode of a material not readily vaporizable and in contact making relation to the extension of said mercury.

3. The combination with a light transmitting envelop having a side chamber, of main terminals communicating with the interior thereof, one of which terminals is electrically connected to a body of mercury in said envelop and extending into said side chamber, a supplemental non-vaporizable electrode, and means for making and breaking electrical connection between the mercury extension in said side chamber and said non-vaporizable electrode.

4. The combination of a light transmitting envelop having a side chamber, main electrodes therefor, one at least of which is of vaporizable material and extends into said side chamber, and a supplemental electrode arranged in said side chamber in co-operative relation to the extension of the vaporizable electrode and formed of a material not readily vaporizable. 45

5. In a vapor electric apparatus, the combination with an exhausted envelop, of a plurality of co-operating electrodes in said envelop, one of which electrodes is an anode and is formed of a material containing 55 graphite and another is a cathode and is formed of a vapor-emitting material.

6. In a vapor electric apparatus, the combination with an exhausted envelop, of a vapor emitting cathode therein, and a co-operating anode formed of a mixture of 60 graphite and a binding material.

7. The combination of an exhausted envelop, a vaporizable cathode therein, and a co-operating anode formed of a material containing 65 graphite.

8. In a gas or vapor apparatus of the character described, a hermetically sealed container having a side chamber, a stationary electrode, with a conducting extension 70 projecting into said chamber and a movable electrode within the chamber to co-operate with said extension, and an electro-magnet exterior to the apparatus, the movable electrode acting as an armature for said magnet. 75

In witness whereof, I have hereunto set my hand this 24th day of February, 1902.

EZECHIEL WEINTRAUB.
